UNITED STATES PATENT OFFICE.

FREDERICK WALDO EDWARDY, OF ATLANTA, GEORGIA.

TOY AND ADVERTISING APPARATUS.

SPECIFICATION forming part of Letters Patent No. 633,821, dated September 26, 1899.

Application filed January 13, 1899. Serial No. 702,056. (No model.)

To all whom it may concern:

Be it known that I, FREDERICK WALDO EDWARDY, a citizen of the United States, residing at Atlanta, in the county of Fulton and State of Georgia, have invented certain new and useful Improvements in Toy and Advertising Apparatus; and I do hereby declare the following to be a full, clear, and exact description of the invention, such as will enable others skilled in the art to which it appertains to make and use the same.

My invention comprehends a combined toy and advertising apparatus, the toy consisting of a box having therein miniature representations of a series of different animals or other figures movable in a circular path, the face or cover of said box having an opening through which the figures may be seen as they pass in succession, and the advertising apparatus consists of a provision for displaying advertising-cards in connection with the movable and moving animals or figures.

In the accompanying drawings, which represent my invention, Figure 1 is a front or face view of the apparatus complete; Fig. 2, a similar view showing the front of the box removed and the partition broken away to show some of the animals in full lines; Fig. 3, a vertical section on the line xx in Figs. 1 and 2.

1 designates a box or case constructed of any preferred material and in any suitable shape (preferably rectangular, as shown) provided with a removable front 2, which constitutes a cover. Centrally in the bottom of the box 1 is fixed a hand or power operated musical box 3, the center shaft of which is provided with radial arms 4 of approximately equal length, on the ends of which are loosely pivoted miniature representations 5 of different animals. These animals may be made of any suitable material, either metal or wood, or they may be cut out of cardboard, according to the grade of toy to be provided, and suitably painted and finished. The figures, of whatever material constructed, are loosely pivoted on the ends of the arms 4 above their centers of gravity, so that they will remain approximately in the same positions during their entire movement around the central axis. In front of said revolving figures is a stationary partition 6 cut out at its upper

part opposite the path of movement of said figures to represent a scene, as an animal-cage, as indicated at 7, and above said cut-out portion I provide means for removably mounting an advertising-card 8, said means consisting, preferably, of clips 9, attached to the partition 6, into which clips the cards are placed and from which they may be conveniently removed to permit an interchange of cards at pleasure. The removable cover 2 has an opening 10, corresponding in size, shape, and position with the opening 7 in the partition 6, together with the advertising-card 8, so that the latter, as well as the movable figures or animals, may be seen from the front.

11 designates a crank-handle which is removably applied to the center shaft of the musical box 3 through openings in the front 2 of the box and in the partition 6.

The front or cover 2 of the box may be (and preferably is) provided with slideways 12 for the reception of a larger advertising-card 13. The cards 8 and 13, being removably mounted on the partition 6 and cover 2, may be removed at will and replaced by others to advertise different enterprises. So, also, the figures 5, mounted on the arms 4, may be removed at will and replaced by others of entirely different character, and by reason of such interchangeability the toy may be changed and varied to suit different tastes, circumstances, or conditions at trifling expense and with little trouble.

Different sets of figures or representations may be supplied with each box at a comparatively trifling expense, by the interchange of which the apparatus is adapted to furnish a variety of entertainment.

The music-box herein shown consists of a drum 14, rigidly secured to the bottom of the case, as shown. This drum carries tongues 15, which are caused to vibrate by means of teeth or pickers 16, carried by barrel or cylinder 17, fixed to the rotary shaft 18, which carries the radial arms 4, to which the figures are pivoted.

Having now described my invention, I claim—

1. A toy consisting of a box or case, a shaft mounted in said case carrying arms and loosely-pivoted figures, and a musical box ar-

ranged around and operated by the rotary shaft.

2. A toy consisting of a box or case, a rotary shaft mounted in said case having a series of arms projecting radially therefrom, a series of figures loosely pivoted to the ends of the arms, and a musical box arranged around and operated by the rotary shaft, substantially as described.

10 3. A toy consisting of a box or case having a removable cover, a rotary shaft mounted in said case carrying radial arms and loosely-pivoted figures, an open partition or frame

in front of the path of the figures representing an animal-cage, a musical box operatively connected with the rotary shaft, and a slide-way on the front of the cover for holding interchangeable advertising-cards, substantially as described.

In testimony whereof I affix my signature ²⁰ in presence of two witnesses.

FREDERICK WALDO EDWARDY.
